(57) **CLAIM**

We claim the ornamental design for a hot and cold food storage cabinet, as shown and described.

DESCRIPTION

FIG. 1 is a right frontal perspective view of the hot and cold food storage cabinet.

FIG. 2 is a front elevation view.

FIG. 3 is a top plan view.

FIG. 4 is a left side elevation view.

FIG. 5 is a right side elevation view.

FIG. 6 is a rear elevation view.

FIG. 7 is a bottom plan view; and,

FIG. 8 is a frontal perspective right side elevation view, showing the doors open with trays in dotted configuration to illustrate the environment of usage of the hot and cold food storage cabinet.

The broken lines shown in the drawings are for illustrative purposes only and form no part of the claimed design.
